LADY'S COAT AND LINING WITH SLEEVES ADAPTED TO BE TIGHTENED ABOUT THE WRISTS

Richard I. Merritt, Forest Hills, N. Y., assignor
of one-half to Ben Taylor, New York, N. Y.

Application April 28, 1949, Serial No. 90,116

1 Claim. (Cl. 2—270)

1

This invention relates to wearing apparel and has particular reference to a lady's coat and lining therefor having sleeves adapted to be tightened about the wrists of the wearer.

The invention has in view a lady's coat of the type having a lining secured to the body thereof continuously along the edges of the open front and across the back adjacent the collar and with the sleeves thereof fitted within the sleeves of the coat and provided with free ends adapted to be tightened about the wrists of the wearer.

Another object of the invention is to provide a lady's coat of the indicated character in which the sleeves terminate in annular cuffs with overlapping ends for varying the size thereof and with interengageable means carried by the ends of the cuffs for tightening the cuffs about the wrists of the wearer.

With the foregoing and other objects in view, reference is now made to the following specification and accompanying drawings in which the preferred embodiment of the invention is illustrated.

In the drawings:

Fig. 1 is a perspective view of a lady's coat provided with a lining constructed in accordance with the invention and illustrating the lining in broken lines within the coat.

Fig. 2 is a perspective view of the lining.

Fig. 3 is an enlarged view of the outer end of one of the sleeves of the lining.

Fig. 4 is an end view of the said sleeve.

Fig. 5 is a fragmentary sectional view taken approximately on line 5—5 of Fig. 3.

Fig. 6 is a sectional view taken approximately on line 6—6 of Fig. 3.

Fig. 7 is a fragmentary sectional view taken approximately on line 7—7 of Fig. 3.

Referring to the drawings by characters of reference, the lady's coat 10 is of any preferred type and as illustrated the same is of long length including the usual body 11 having a front opening 12, sleeves 13 and a lining 14.

The lining 14 includes a body 15 which is similar in formation to the body 11 of the coat and is connected therewith longitudinally of the edges 17 and 18 and across the back adjacent the collar 19. The lining 14 also includes sleeves 16 which are fitted within the sleeves 13 of the coat.

The body 15 of the lining is made up of inner 50 and outer plies 20 and 21 which are secured together continuously along the forward edges 22 and 23 and across the top 24. The inner ply 20 projects below the outer ply 21 and the same is secured thereto by a line of stitching 25 extending

continuously about the bottom of the outer ply. The sleeves 16 are connected with the body 15 of the lining in the usual manner and each consists of an inner ply 26 extending from the shoulder to a cuff 27 while the outer ply 28 extends from the shoulder to slightly below the elbow with an outer ply 29 connected between the cuff 27 and the aforesaid outer ply 28 of the sleeves.

The outer ply 21 of the body 15 and the outer 10 ply 28 of the sleeves 16 are preferably made of warm material such as wool or the like while the inner ply 26 of the body 15 and the inner ply 26 of the sleeves together with the cuffs 27 and the outer ply 29 of the sleeves are preferably made 15 of a facing material such as silk, rayon and the like. The upper portions of the sleeves 16 of the lining snugly fit within the sleeves 13 of the coat while the lower portions thereof loosely fit within the lower ends of the sleeves. The cuffs 27 include ends 30 and 31 which are arranged in overlapping relation and are adjustable relative to each other so as to vary the size of the cuffs. The sleeves adjacent the cuffs 27 have overlapping portions 32 and 33 which portions are unconnected so that the lower ends of the sleeves together with the cuffs 27 may be tightened about the wrists of the wearer.

In order to connect the ends of the cuffs together in overlapping relation for tightening the same about the wrists of the wearer, interengageable fastening means are provided on each of the cuffs which preferably consist of a runner 34 having a hingedly connected lever 35 secured to the end 31 of the cuff and a longitudinally extending member 36 secured upon the outer face of the end portion 30 of the cuff and having a series of transversely extending longitudinally spaced bars 37 adapted to be selectively engaged by the lever 35 for securing the ends 30 and 31 of the cuffs in overlapping connected relation.

The lining 14 may be permanently affixed to the body 11 of the coat, or as illustrated, the lining may be of the removable type. For this purpose the body 11 of the coat adjacent the edges 17 and 18 forming the front opening 12 of the coat and the forward edges 22 and 23 of the lining are provided with interengageable slide fastening means indicated generally by the reference character 38. Constructed in this manner the body 15 of the lining is adapted to be secured to the coat continuously along the forward edge 22 and across the top 24 and the forward edge 23.

What is claimed is:

In an article of the character described, a lady's coat including a coat body and sleeves, a remov-

able lining including sleeves consisting of upper and lower portions, the upper portion of the sleeves snugly fitting within the sleeves of the coat, the lower portion of the lining sleeves being relatively flexible and loosely fitting the sleeves of the coat and being free for relative movement with respect to the coat sleeves, cuffs carried by the lower ends of the lining sleeves having end portions arranged in overlapping relation for varying the size of the cuffs, and interengageable fastening means carried by the end portions of the cuffs for ad-

5 justably tightening the cuffs about the wrists of the wearer.
